OF NEW YORK, N. Y., A CORPORATION OF NEW YORK.

DISPLAY CARD.

1,406,944.

Specification of Letters Patent. Patented Feb. 14, 1922.

Application filed June 29, 1920. Serial No. 392,726.

To all whom it may concern:

Be it known that I, JOSEPH DOMBER, a citizen of the United States, and resident of the city of New York, borough of Manhattan, in the county of New York and State of New York, have invented a new and Improved Display Card, of which the following is a full, clear, and exact description.

My invention relates to display cards, and 10 more particularly that type of device by means of which it will be possible to arrange a piece of fabric in a manner simulating the appearance of a finished garment.

In connection with display cards, it is a 15 well appreciated fact that any number of devices have been proposed which are provided with a cut out portion conforming to the outlines of a miniature finished garment. These cards or devices were adapted to have 20 a piece of cloth arranged against their rear face so that upon viewing the device from the front a customer might be enabled to judge the appearance of a finished garment constructed of the particular design of cloth 25 which he had in mind.

These devices have presented a defect, however, in that the cloth has appeared in a flat surface thus failing to give an accurate idea of the garment as it would appear when 30 finished, in view of the fact that the front of the garment presents curved portions conforming to the body of the wearer which curved portions did not appear upon any of the devices aforementioned being used.

With this in view, I have constructed a 35 display card, which may be utilized by dealers or in window display, and by means of which a piece of cloth may be presented in such a manner as to more nearly conform to 40 the appearance of a completed garment, although my improved card may readily be utilized as a cover plate for the folder receiving a number of pieces of cloth, one of the pieces being shown in the manner aforementioned.

Reference is had to the attached sheet of drawings as illustrating one practical embodiment of my invention and in which drawings,

50 Figure 1 is a front view of a display card constructed in accordance with my invention, and showing a piece of cloth applied thereto, to the improved result aforementioned.

Figure 2 is a sectional view taken along 55 the line 2—2 of Figure 1, and

Figure 3 is a sectional view taken along the line 3—3 of Figure 1.

In these views the reference numeral 5 indicates a card or plate of any desired material, which is formed with a cutout portion 60 simulating in outline, the trunk of a body from which members 6 are shown as extending with a view of illustrating the limbs of the trunk.

Figure 65 A sheet of material 7 conveniently serves in the accompanying illustration, as a securing medium for a layer of cloth 8, which is interposed between the outer face of this sheet and the inner face of the card 5.

To now arrange a layer of cloth 8 in a manner in which the same will appear in a more natural arrangement than has been heretofore accomplished, it will be noted 70 that parts of the layer of cloth directly coincident with the cutout portion of the card 5 are arranged with a certain fullness, as has been indicated by the reference numeral 9, so that the material might be said to be 75 "puckered" at this point.

By this arrangement a natural fullness is 80 imparted to the display portions of the layer of cloth, which simulates in a most highly natural manner, the effect of a garment applied to the body of a wearer. It will be 85 readily understood that any relatively large stretch of cloth arranged in the manner aforescribed would fail to hold its natural "puckered" position without some intermediate retaining or supporting means. 90 This is due to the fact that a defect such as 95 this is liable to come into being, assuming that my invention were used in connection with folders, which naturally in shipment are arranged in stacks, and by virtue of the pressure exerted by one card upon the next underlying card, the fullness or puckering of the layer of cloth would for the most part, be crowded so as to extend adjacent one 100 of the edges of the cutout portion 5.

Having this defect in mind, I now provide such a supporting means, which supporting means shall be in the nature of structure enhancing the appearance of the card. Reference is had now more particularly to Figure 1, in which it will be noted that the cutout portion simulating the trunk of a body 105 is provided at that point at which the waist

line of an actual wearer would come into existence with a belt 10, which belt preferably forms an integral portion of the card 5, and is shaded or otherwise treated to correspond to the figure or member the member which it is intended to represent.

If it is desired, a panel 11 may extend from the belt 10 and overlie the layer of cloth 8. It will be understood that glue or 10 any other suitable affixing medium is applied to the under face of the belt 10 and panel 11, where the latter is used, or to the upper face of the layer of cloth 8, at a point directly underlying these members, so as to 15 cause an intimate engagement between these elements. Thus, the layer portion of the "puckered" cloth is held so that no great amount of movement is permitted, thus maintaining the desired effect.

20 To now properly support in a similar manner the upper portion of the cloth, the head 12 has an extending portion 13 directly underlying the same. This extending portion is formed so as to simulate the neck and exposed portion of the chest of the wearer, and projects into the cutout portion of the card 5, it being understood that a suitable securing agent is utilized between the under-side of this part and the upper surface of 25 the cloth to again support the latter in the manner described in the preceding paragraph.

From the foregoing it will be appreciated that I have constructed a display card which 30 may be utilized for any convenient purpose, and which will permit of the arrangement of cloth in connection with the same in a most highly natural manner, and which cloth will not become displaced even when 35 subject to the hardest usage.

It will further be appreciated that I have 40 constructed a display card in which the outline or contour of the cutout portion may be varied to simulate the contour of any desired garment, a belt portion 10 of any desired design being used for supporting the layer of cloth substantially intermediate the cutout portion of the card, any desired extending portion 13 being used for serving a similar 45 purpose in connection with the upper part of the cloth layer 8.

What I claim as new is:

1. A display device including a card formed with a cutout portion, a layer of material adapted to be arranged adjacent said card and secured thereto at the rear of the edge defining said cutout portion and a strip secured to said card and adapted to extend across said cutout, said material being secured to and in part supported by said strip. 55

2. A display device including a card formed with a cutout portion, a layer of material arranged adjacent said card and secured thereto at the rear of the edge defining said cutout portion, a panel, a strip secured to 60 said panel, said strip being connected to said card and extending across said cutout portion, said material engaging and being supported in part by said panel and said strip. 65

3. A display device including a card 70 formed with a cutout portion, a layer of material arranged adjacent to said card and secured thereto at the rear of the edge defining said cutout portion, said card being formed with an extended portion projecting into 75 said cutout portion, said material engaging and being supported in part by said extending portion.

4. A display device including a card with a cutout portion, a layer of material 80 arranged adjacent to said card and secured thereto at the rear of the cutout portion thereof, said material being puckered within said cutout portion, and means associated with said card and extending into the cutout portion thereof, for engaging said material and partially supporting the same. 85

5. A display device, including a card formed with a cutout portion, a layer of cloth arranged to the rear of said card and 90 secured thereto at a point adjacent the edge defining said cutout portion, said cloth projecting into said cutout portion, said cloth being puckered within said cutout portion, said card being formed with a strip adapted 95 to project across said cutout portion and simulating the belt of a garment, said card being further formed with an extending portion simulating the neck of a wearer, said cloth engaging the under side of said extending and projecting portions. 100

JOSEPH DOMBER.
